UNITED STATES PATENT OFFICE.

PETER GHINELLI AND ANGELO BUCHIGNANI, OF SWATARA STATION, PENNSYLVANIA.

STOPPING APPARATUS FOR MOTOR-CARS.

1,132,332.

Specification of Letters Patent.

Patented Mar. 16, 1915.

Application filed June 10, 1914. Serial No. 844,281.

To all whom it may concern:

Be it known that we, PETER GHINELLI and ANGELO BUCHIGNANI, citizens of the United States, residing at Swatara Station, 5 in the county of Dauphin and State of Pennsylvania, have invented new and useful Improvements in Stopping Apparatus for Motor-Cars, of which the following is a specification.

10 This invention relates to improvements in stopping apparatus for motor cars and has particular application to signal controlled apparatus of this character.

In carrying out the present invention, it is 15 our purpose to provide apparatus of the class described whereby the propelling power of the motor car will be cut off and the brakes applied in the event of the car or train passing a danger signal and where- 20 by a signal will be sounded simultaneously with the cutting off of the propelling power and the application of the brakes.

It is also our purpose to provide stopping 25 apparatus for motor cars which will embrace the desired features of simplicity, efficiency and durability, which may be installed and maintained at a minimum expense and which will operate effectively under all conditions.

30 With the above and other objects in view, the invention consists in the construction, combination and arrangement of parts hereinafter set forth in and falling within the scope of the claims.

35 In the accompanying drawings; Figure 1 is a fragmentary top plan view of a trackway showing the relative positions of the track instrument and signal. Fig. 2 is a fragmentary longitudinal sectional view 40 through the trackway showing the instrument in side elevation. Fig. 3 is a cross sectional view on the line 3—3 of Fig. 1. Fig. 4 is a diagrammatic view of the car carried mechanism. Fig. 5 is a view in side elevation 45 of the circuit closer. Fig. 6 is a sectional view on the line 6—6 of Fig. 5. Fig. 7 is a similar view on the line 7—7 of Fig. 5. Fig. 8 is an enlarged fragmentary plan view 50 showing the connection between the motor and brake valve. Fig. 9 is a perspective view of a detail of the car carried mechanism.

Referring now to the drawings in detail, 1 designates a trackway which is preferably 55 divided into blocks and located at the entrance to each block and controlling traffic

thereinto is a semaphore 2 comprising a standard 3 and a signal blade 4 pivoted upon the standard adjacent to the upper end thereof and capable of movement to danger 60 and clear positions. Disposed between the lines of rails of the trackway at the entrance to each block is a track instrument comprising a substantially rectangular base plate 5 arranged longitudinally of the track and 65 equipped with upwardly projecting pivot ears 6, 6 spaced apart and having the openings therein alining axially with each other and having the axes thereof lying parallel with the adjacent lines of rails. Journaled 70 in the ears 6 are axially alining trunnions 7 carried by the opposite extremities of an obstacle plate 8 capable of swinging movement to vertical and horizontal positions and adapted, when in vertical position, to 75 lie parallel with the lines of rails of the track. Depending from the lower edge of the obstacle plate 8 and working within a transverse slot 9 formed in the base plate 5 is an arm 10 having the lower end thereof 80 connected through the medium of a rod 11 with one limb of a bell crank lever 12 pivoted for swinging movement upon a suitable support and having the remaining limb thereof connected through the medium of 85 suitable link mechanism 13 with the signal blade 4 of the adjacent semaphore 2. When the signal blade 4 is actuated to danger position motion is transmitted to the arm 10 through the link mechanism 13, bell crank 90 lever 12 and rod 11 and the obstacle plate 8 swung to vertical or active position. On the other hand, when the signal blade is actuated to clear position, the plate is swung to a horizontal plane or inactive position. In 95 this embodiment of our invention, we have shown the car carried stopping mechanism as installed in a steam driven locomotive and in this connection we wish it to be understood that this mechanism may be installed in locomotives driven by electricity, air, gas, liquid fuel and the like without departing from the spirit of our invention. In the present instance, the car carried stopping mechanism comprises an electric motor 100 14 connected in an electric circuit 15 and having one end of the armature shaft thereof of projecting outwardly of the adjacent extremity of the casing. Fast upon the projecting end of the armature shaft is a worm 110 16 meshing with a worm wheel 17 keyed upon a countershaft 18 journaled in hori-

zontally alining bearings 19 and lying in a plane parallel with the armature shaft of the motor.

20 designates the steam main leading from 5 the steam dome of the boiler to the drive cylinders of the locomotive and located in such main is a gate valve 21 normally open and adapted, when closed, to cut off communication between the steam space of the 10 boiler and the drive cylinders. Connected with the casing of the gate valve 21 and projecting outwardly therefrom is a substantially U-shaped yoke 22 having the interconnecting member thereof formed with 15 an opening alining axially with the bonnet of the gate valve to receive the stem 23 of the gate. Fixed upon the stem 23 within the yoke 22 is a disk 24, while encircling the stem between the disk 24 and the interconnecting member of the yoke is a coiled expansion spring 25 adapted to slide the gate to closed position. The outer end of the stem 23 is bent at right angles to itself as at 26 and journaled in such bent portion is a 20 roller 27 normally resting against one face of a sector 28 keyed upon one end of the shaft 18 and normally disposed in the path of movement of the bent end 26 of the stem 23 to hold the latter against sliding movement under the action of the expansion 25 spring 25 whereby the gate is held normally in open position. The brake pipe or train line air pipe of the motor car or train is indicated at 29 and located in such pipe 30 and normally closed is a gate valve 30 having the end of the stem 31 thereof bent at right angles to itself and formed to provide a tooth 32 meshing with a worm 33 fast upon the other end of the shaft 18. When the circuit 15 is closed and the motor 14 energized 35 the shaft 18 is revolved through the action of the worm 16 and worm wheel 17 and in the rotation of the shaft 18 the sector 24 is swung out of the path of the bent end 26 of the stem 23 whereby the spring 25 reacts and slides the gate of the valve 21 to closed 40 position, thereby cutting off communication between the steam space of the boiler and the engine cylinders. Simultaneously with 45 the swinging of the sector to release the gate of the valve 21 the worm 33 in engagement with the tooth 32 on the stem 31 of the gate of the valve 30 slides the gate of the last-mentioned valve to open the train line air 50 pipe and so effects a reduction of pressure therein whereby the brakes will be applied to the wheels. The shaft 18 also controls a circuit breaker connected in series in the circuit 15 which, in this instance, comprises 55 a stationary contact 34 secured to and insulated from an arm 35 carried by the casing of the valve 30 and projecting outwardly therefrom parallel with the stem 31 of the gate, and a movable contact 36 fixed to and 60 insulated from the stem 31 and normally en-

gaging the stationary contact 34 and adapted to ride off of such stationary contact in the outward movement of the stem 31 under the action of the worm 33 to break the circuit 15 of the motor 14 succeeding the opening of 70 the valve 30 and closing of the valve 31 whereby the motor will be deenergized.

37 designates a substantially rectangular base plate suitably secured to the under structure of the motor car and disposed in 75 a horizontal plane. Uprising from the base plate 37 adjacent to one end thereof and spaced apart longitudinally of such plate are bearings 38 and mounted within the bearings and capable of sliding movement 80 therein is a plunger rod 39, while upstanding from the base plate 37 adjacent to the opposite end thereof and spaced apart longitudinally of such plate are bearings 40 in which is mounted for sliding movement a 85 plunger rod 41. Secured to the confronting ends of the plunger rods 39 and 41 are contacts 42 connected in series in the circuit 15 and adapted to close such circuit when in engagement with each other. Encircling the 90 plunger rod 39 between the bearings 38 is a coiled expansion spring 43 having one end abutting one of the bearings and the opposite end in engagement with a shoulder 44 formed on the plunger rod and adapted to 95 limit the movement of the plunger rod under the action of the spring 43. Formed on the remaining end of the plunger rod 41 is a disk 45 and spaced apart from the adjacent bearing 40 and interposed between such disk 100 and bearing is a coiled expansion spring 46, while formed on the plunger at the opposite side of the adjacent bearing 40 is a shoulder 47 adapted to limit the movement of the plunger rod 41 under the action of the 105 spring 46. Depending from the lower surface of the base plate 37 at the last-mentioned end thereof are vertical posts 48 spaced apart and connected with the lower extremities of the posts 48 is a supporting 110 plate 49 formed with an opening alining with an opening formed in the adjacent end of the base plate 37 and journaled in these alining openings and capable of rotation therein is a vertical shaft 50 having the 115 lower end thereof equipped with an arm 51 projecting at right angles to the shaft 50 and lying, normally, in the plane at right angles to the path of travel of the car. Fast to the upper end of the shaft 50 is an eccentric 120 52 engaging the disk 45. Fixed to the shaft 50 immediately above the supporting plate 49 is a ratchet wheel 53 and engaging the teeth of the ratchet wheel 53 is a dog 54 acting to hold the shaft 50 against turning 125 movement in one direction. Also fixed to the shaft 50 above the ratchet wheel 53 is a pinion 55 meshing with the teeth of a rack bar 56 mounted for sliding movement with 130 in suitable horizontally alining guides car

ried by the posts 48, a coiled expansion spring 57 having one end fastened to the rack bar and the opposite extremity secured to a bracket depending from the base plate 5, such spring acting through the medium of the rack bar 56 and pinion 55 to hold the shaft 50 against turning movement in the opposite direction.

In practice, when the motor car passes a danger signal, the arm 51 impacts against the adjacent edge of the obstacle plate 8 and so rocks the shaft 50 against the action of the spring 57. In the movement of the shaft 50 under the action of the obstacle plate the cam 52 in engagement with the disk 45 slides the plunger rod 41 against the action of the spring 46, thereby engaging the contacts 42 with each other and so closing the electric circuit 15 with the effect to energize the motor and operate the valves 21 and 30 as previously described. By means of the plunger rod 39 and the spring 43 the shock, incident to the engagement of the contacts 42, is eliminated.

From the foregoing description taken in connection with the accompanying drawings, the construction, mode of operation and manner of employing our invention will be readily apparent. It will be seen that we have provided automatic stopping mechanism for motor cars whereby the propelling power of the motor car will be cut off and the air brakes applied in the event of such car running by a danger signal and wherein the car carried mechanism will be automatically cut out of service immediately succeeding the cutting off of the propelling power and application of the brakes. In the present instance, an audible signal 58 in the form of a bell is connected in parallel with the circuit 15 so as to advise the engineer or train crew of the operation of the stopping mechanism.

While we have herein shown and described one preferred form of our invention by way of illustration, we wish it to be understood that we do not limit or confine ourselves to the precise details of construction herein described and delineated, as modification and variation may be made within the scope of the claims without departing from the spirit of the invention.

We claim:

1. In stopping apparatus for motor cars, means for cutting off the propelling power

of the car, a shaft capable of rotation, a sector carried by said shaft and holding said means normally inactive, a motor for rotating said shaft to relieve said means of the influence of said sector, and means for actuating said cutting off means upon the release thereof. 60

2. In stopping apparatus for motor cars, means for cutting off the propelling power of the car, a shaft capable of rotation, a sector carried by said shaft and holding said means normally inactive, a motor for rotating said shaft to relieve said means of the influence of said sector, and a spring for actuating said cutting off means upon the release thereof. 65

3. In stopping apparatus for motor cars, means for cutting off the propelling power of the car, a shaft capable of rotation, a sector carried by said shaft and holding said means normally inactive, a motor for rotating said shaft to relieve said means of the influence of said sector, an electric circuit for said motor, and a circuit closer for closing said circuit. 75

4. In stopping apparatus for motor cars, means for cutting off the propelling power of the car, a shaft capable of rotation, a sector carried by said shaft and holding said means normally inactive, a motor for rotating said shaft to relieve said means of the influence of said sector, an electric circuit for said motor, a circuit closer for closing said circuit, and means for breaking said circuit immediately succeeding the operation of the motor. 80

5. In stopping apparatus for motor cars, means for cutting off the propelling power of the car, a shaft capable of rotation, a sector carried by said shaft and holding said means normally inactive, a motor for rotating said shaft to relieve said means of the influence of said sector, an electric circuit for said motor, a circuit closer for closing said circuit, and means operable from said motor for breaking the circuit thereof immediately succeeding the operation of the same. 95

In testimony whereof we affix our signatures in presence of two witnesses.

PETER GHINELLI.
ANGELO BUCHIGNANI.
